UNITED STATES PATENT OFFICE.

SELDEN R. HOPKINS, OF CHICAGO, ILLINOIS.

ADJUSTABLE SHADE OR MAP ROLL.

1,253,382.

Specification of Letters Patent. Patented Jan. 15, 1918.

Application filed February 1, 1917. Serial No. 145,928.

To all whom it may concern:

Be it known that I, SELDEN R. HOPKINS, a citizen of the United States, and a resident of the city of Chicago, in the county of Cook and State of Illinois, have invented certain new and useful Improvements in Adjustable Shade or Map Rolls; and I do hereby declare that the following is a full, clear, and exact description of the same, 10 reference being had to the accompanying drawings, and to the numerals of reference marked thereon, which form a part of this specification.

This invention relates to an improved 15 construction of rolling shade, map or display sheet wherein the sheet is rolled upon a suitable roller, which is adjustable so that by proper adjustment and positioning of the roller, different parts of the sheet may be 20 exposed and different lengths thereof as desired for any purpose whatsoever. Particularly in the roller type of maps, it is often desirable to bring a certain portion of the map to an easily accessible point of view, 25 and this is not possible where the map roll is in a fixed position, and may necessitate unrolling of the entire map for the purpose, and as a consequence, the portion desired for inspection is generally in an inaccessible 30 position. Of course, the construction is adaptable for any use wherein a roller adjustment of a display sheet or surface is desired, but for the purposes of illustration, I have shown my construction used as a 35 window shade so as to illustrate the possibilities of operation thereof.

It is an object therefore of this invention 40 to provide a roller construction wherein the roller is adjustable to different positions, and from any position thereof the sheet or 45 surface wound thereon may be unrolled therefrom and to any height or position desired to expose a predetermined area of surface.

It is also an object of this invention to 45 construct a shade roller or other mechanism wherein a roller is mounted between suitable upright guides, and at its ends is provided with thimble or drum members around 50 which cables are wound to effect a rotational adjustment of the roller, and with certain cables connected to the sheet which is wound on the roller to effect adjustment

thereof independent of adjustment of the roller by said cables.

55

It is also an object of this invention to construct a roller or other mechanism wherein in a roller is provided adapted to be rotated by cables wound around drums formed at the end thereof whereby rotation of the 60 roller serves to effect adjustment of a sheet wound thereon or in the event of said sheet being held stationary, serves to effect adjustment or change the position of the roller, so that any portion of the sheet on the 65 roller may be unwound therefrom and placed at any desired position by bodily adjustment of the roller and sheet, or by adjustment of the sheet from the roller when held at a fixed position.

70

It is a further object of this invention to construct a roller mechanism wherein a roller is adjustable according to rotational movements imparted thereto, and with a sheet wound about said roller adjustable 75 bodily with said roller or adjustable from said roller when said roller is held in fixed position.

75

Other and further important objects of the invention will be evident from the disclosures in the drawings and specification.

80

The invention (in a preferred form) is illustrated in the drawings and hereinafter more fully described.

On the drawings:

Figure 1 is a fragmentary elevation of a window with a shade mechanism embodying the principles of my invention.

85

Fig. 2 is a fragmentary detail section taken on line 2—2 of Fig. 1.

90

Fig. 3, is a fragmentary detail section taken on line 3—3 of Fig. 1, with parts in elevation and parts omitted.

Fig. 4, is an enlarged fragmentary rear view with parts in section, of the roller 95 mechanism mounted in its guides and with parts omitted.

Fig. 5, is a fragmentary detail section of one end of the roller.

Fig. 6 is a detail view partly in section 100 of one end of the stick of the sheet wound upon the roller.

Fig. 7 is a sectional detail through one of the guides at the upper end thereof.

Fig. 8 is a detail section on line 8—8 of 105 Fig. 3.

Fig. 9 is a sectional detail on line 9—9 of Fig. 8.

Fig. 10 is a top plan view of the mechanism shown in Fig. 9.

5 As shown on the drawings:

The window frame shown in Fig. 1, consists of upright side members 1, a sill 2, and a top cross member 3, and slidably in the frame is an upper sash 4, and a lower sash 5. Secured to the respective side frame uprights 1, on each side of the window frame, are channel guides 6. Mounted transversely of the window frame and adjustable therein, is a roller 7, and on each end thereof secured by a screw 8, as shown in Fig. 5, are double thimble members 9. As clearly shown in Fig. 4, the inner groove of each of the double thimbles 9, engages with the inturned flanges of the guides 6, and the outer grooved portion of said thimbles each have wound therearound cables 10, which, when unwound from said thimbles, serve to impart a rotational movement to the roll 7. Secured to the upper end of each of the channel guides 6, are cord or cable guide plates 11, each provided with apertures 12 and 13, therethrough, respectively. Said cables 10, are led upwardly and through the apertures 13, and then over and around a cross-pin or roller 14, mounted in the upper end of one of the guide channels 6, and downwardly to the lower end of the channel.

Also extending transversely of the window frame is a stick 15, provided with gudgeons 16, at its ends, which project through the vertical slots of the channel guides 6, whereby said stick is guided in its movement, and secured to said gudgeons 16, at each end of the stick, are cables 17. Said cables 17, are led upwardly through the apertures 12, of the cable or cord guide plates, and the cable 17, at one side, is led from its aperture 12, of one guide plate over and across the window frame at the upper end thereof, as clearly shown in Fig. 4, and through the aperture 12, of the other guide plate at the other side of the window. Both of said cables 17, are then led upwardly and around a roller or pin 18, mounted in the upper end of one of the channel guides 6, and then downwardly and within the channel guide to the lower end thereof.

A sheet of any material 19 such as a window shade, map, or display surface, may be secured to and wound around the roller 7, and the outer edge of said sheet or shade surface 19, is attached to the stick 15. Mounted upon each of the upright channel guides 6, near the lower end thereof, at its opening in the outer edge of each are projecting plates or lugs 20, between each pair of which is journaled a roller 21, having serrations or teeth 22, along a portion 65 of the periphery thereof, and said respective

cables 10 and 17, are led downwardly and outwardly from the guides between said plates and beneath said serrated rollers at each side of the window frame, as clearly shown in detail in Fig. 9.

The operation is as follows:

The cables 10, the ends of which are fastened to and are wound within the outer groove of the thimbles 9, of the roller 7, when pulled outwardly through the aperture provided therefor at the lower end of one of the guides 6, unwind from the thimbles and serve to impart a rotational movement to the roller 7, to cause said roller to wind the shade material 19, therearound. Thus, if the stick 15, is in a fixed position such winding of the shade material 19, on the roll, will cause the roll to elevate itself toward the stick 15. On the other hand, if the cables 10, are released, the roll 7, will move downwardly by gravity, thereby unwinding the shade material 19, therefrom, provided the stick 15, is held stationary, and at the same time winding the cable or cords 10, upon the thimbles 9. Both of said cords or cables 10, are accessible at the right hand side of the window at the lower end of one of the guides 6, referring to Figs. 1 and 2. The cable 10, which is wound on the thimble at the left hand end of the roller 7, is led across at the upper end of the window frame, as shown in Fig. 4, to and through the apertures 13, of the cable guide plates, together with the cable 10, which is wound upon the thimble at the right hand end of the roller.

Inasmuch as the stick 15, is supported by the cables 17, at each of its ends, the cable 17, at the right hand side of the stick, referring to Figs. 1 and 2, is led from the aperture 12 of one guide plate across the upper end of the window frame and through the aperture 12, of the other guide plate, together with the other cable 17, for the left end of the stick. Said cables are trained upwardly over the roller 18, and then downwardly in the guide so that both are accessible at the same point at the lower end of the guide 6. The stick may be adjusted to any fixed position desired, that is, permitted to move downwardly by gravity, and moved upwardly by the cables 17, and then the roller 7, may be manipulated by the cables 10, to unroll any desired portion of the shade or map 19. When used as a shade construction, it is obvious that any portion of the window may be shaded by proper positioning of the stick and roller under the control of the cables or cords 17 and 10, respectively. The serrated rollers 21, mounted at the lower end of each of the channel guides 6, serve as means to clamp the respective cables 10 and 17, to hold said cords from movement, and thereby hold said stick 15, and roller 7, in any desired adjusted 130

position. Release from said serrated rollers is readily gained by pulling outwardly upon the cable, and then holding the same closely inwardly to the guides as the cables are to be fed inwardly within the channels for an adjustment movement of the stick or roller.

I am aware that the details of construction may be varied through a wide range without departing from the principles of my invention, and I therefore do not pur-
10 pose limiting the patent granted otherwise than necessitated by the prior art.

I claim as my invention:

1. In a device of the class described, up-
15 right channel guides, a roller, thimbles se-
cured to each end thereof and disposed in
the channels of said guides, cables wound
upon each of said thimbles with one of
20 said cables led from the channel of one of
said guides to the channel of the other guide
whereby said cables both are accessible at
the same point, a sheet wound upon said
25 roller, a stick secured at the edge of said
sheet, and cables attached to each end of
said stick with one of said cables led from
one of said channel guides into the other
thereof, whereby said cables also are acces-
30 sible at the same point.

2. In a device of the class described, up-
35 right channel guides, a roller, thimbles se-
cured to each end thereof and disposed in
the channels of said guides, apertured guide
plates in the upper ends of said channel
guides, cables wound upon each of said
40 thimbles with one of said cables led from
the channel to one of said guides through its
apertured guide plate to the channel of
the other guide and through its apertured
guide plate, whereby said cables both are
45 accessible at the same point, a sheet wound
upon said roller, a stick secured at the edge

of said sheet, and cables attached to each
end of said stick with one of said cables led
from one of said channel guides through
its apertured guide plate into the other
thereof and through its apertured guide
50 plate, whereby said cables also are acces-
sible at the same point.

3. In a device of the class described, up-
55 right channel guides, a roller, thimbles se-
cured to each end thereof and disposed in
the channels of said guides, apertured guide
plates in the upper ends of said channel
guides, cables wound upon each of said thim-
60 bles with one of said cables led from the
channel to one of said guides through its
apertured guide plate to the channel of
the other guide and through its apertured
guide plate, whereby said cables both are
65 accessible at the same point, a sheet wound
upon said roller, a stick secured at the edge
of said sheet, cables attached to each end
of said stick with one of said cables led
from one of said channel guides through
70 its apertured guide plate into the other
thereof and through its apertured guide
plate, whereby said cables also are acces-
sible at the same point, said roller cables
passing down the channel guide at one side
75 and said stick cables passing down the chan-
nel guide at the other side, and clamps fixed
to said channel guides near their lower ends
for engaging cables detachably to retain
them in any adjusted position.

In testimony whereof I have hereunto
subscribed my name in the presence of two
subscribing witnesses.

SELDEN R. HOPKINS.
